TOILET BOWL

William August Henn, Evansville, Ind.

Application April 4, 1934, Serial No. 718,998

3 Claims. (Cl. 4—257)

This invention relates to a toilet bowl and has for an object to provide an improved toilet bowl which can carry and discharge all the water coming from the flush tank in the event that the trap of the bowl should become clogged.

A further object of this invention is to provide a toilet bowl which cannot overflow and discharge its contents on the floor of the bathroom in the event that the trap of the bowl should become clogged by any obstructions.

A further object of this invention is to provide a toilet bowl with a plurality of by-passes capable of conducting the entire water to the soil pipe in case the trap of the bowl should be obstructed, which by-passes, however, will ordinarily not conduct any water, or only a very small portion thereof, so long as the bowl trap is in good working condition.

A further object of this invention is to provide by-passes in a toilet bowl for carrying the water around the bowl trap, which by-passes have a greater total area than the area of the trap.

Still a further object of this invention is to provide a clean out at the crown of the bowl trap making it possible to remove any obstruction and clean out the bowl trap without the necessity of removing the bowl from the floor.

With the foregoing and other objects in view, as will hereinafter become apparent, this invention comprises the constructions, combinations and arrangements of parts, hereinafter set forth, disclosed and shown on the accompanying drawing. In this drawing,

Figure 1 is a vertical sectional view of the improved water closet bowl,

Figure 2 is a vertical view of the by-pass for the toilet bowl,

Figure 3 is a rear view of the bowl, partly broken away to show one of the by-passes, and

Figure 4 is a sectional view taken on the line 4—4 of Figure 2.

There is shown at 10 the toilet bowl constituting this invention. This bowl 10 has a water inlet 11 adapted to be connected up to a supply of water such as a flushing tank or water pressure line, or the like.

A by-pass 15 also connected to the inlet 11 leads directly to the trap 16 discharging therein through a jet opening 17. This jet opening 17 assists in forcing the contents of the trap 16 to the outlet leg 18 of the trap and to the bowl outlet 19. It often happens that the trap 16 of the toilet may become clogged or stuffed by some obstruction, preventing the flow of water therethrough.

In the usual toilet bowl when this happens the

water level 13 flows over the toilet bowl onto the floor of the lavatory or bathroom soiling and damaging the floor as well as penetrating to the ceiling below causing additional damage.

In order to prevent this damage this invention provides a pair of by-passes situated on either side of the bowl trap 16 and leading from a by-pass inlet 20 located in the bowl 14 to a by-pass outlet 21 located in the toilet bowl outlet 19. It will be further observed that the inlet by-pass leg 20 is substantially parallel in direction to the inlet leg of the trap 16 and that the outlet by-pass leg 21 is substantially parallel to the outlet leg of the trap 16. Also that the discharge outlet of the by-pass outlet 21 lies vertically above at least in part, over the bowl outlet 19. As will be apparent from Figure 3, the side walls of the main trap are vertically disposed and the inlet openings leading to the by-pass inlet 20 are vertical. As a result of this construction the excrement cannot lodge in and block the opening as it washes back and forth when the water first begins to flush the bowl and before there is sufficient pressure to flush it. Furthermore, if the trap 16 becomes blocked the flow of water does not have to reverse itself, but instead is taken by the inlet by-pass 20 in substantially the same direction as the inlet leg of trap 16, and then discharges at the end of the outlet passage 21 so as to fall directly into the bowl outlet 19 and not be subject to further obstructions or corners, thereby insuring against overflow. These by-passes 22, it will be observed, are likewise in the form of a trap or inverted U, so that they will not lower the level of the water 13 in the toilet bowl 14.

It will be further observed that these by-passes 22 are out of the direct line of flow of the water 13 through the bowl 14 to the trap 16 on its way to the outlet 19, and further, that the combined cross sectional area of these two by-passes is greater than the cross sectional area of the trap 16. With this construction the water 13 will flow through the trap 16 to the down leg 18 and outlet 19 so long as the trap 16 is unobstructed. Should the trap 16 become obstructed for any reason, then the water which would ordinarily overflow the sides of the bowl to damage the floor, will instead be diverted through the by-pass inlet 20 through the by-pass 22 and to their by-pass outlets 21 leading to the bowl outlet 19, thus by-passing the water about the obstruction and preventing the overflow. It will be further noted that the by-passes as located on opposite sides of the trap 16 do not materially increase the bulk of the

toilet and do not require any extra space in the room not already occupied by the toilet bowl.

In order to remove the obstruction that may be present in the trap 16, a clean-cut 23 is located 5 in the crown 24 of the trap 16. This clean-out

23, as will be observed, includes an aperture 25 of sufficient size to permit the entrance of fishing tools for removing the obstruction. This aperture 25 is normally closed by a plug 26 carried 10 by the clean-out closure member 23, the plug 26 being preferably of resilient sealing material such as soft rubber, so as to prevent the escape of any noxious gases coming into the trap 16 from the soil pipe connected to the outlet 19.

15 As a result of this invention the by-passes 22 prevent the overflow of the toilet water 13 onto the floor of the toilet room. The by-pass 15 assists in emptying the trap 16, while the clean-out 20 23 permits any obstruction in the trap 16 to be removed without the necessity of taking up the bowl 18 or disturbing the plumbing.

The novel features and the operation of this device will be apparent from the foregoing description. While the device has been shown and 25 the structure described in detail, it is obvious that this is not to be considered limited to the exact form disclosed and that changes may be made therein within the scope of what is claimed without departing from the spirit of the invention.

30 Having thus set forth and disclosed the nature of this invention, what is claimed is:

1. As an article of manufacture, a toilet bowl having a bowl bottom, a bowl discharge outlet, an inverted U trap connecting said bowl portion to said bowl discharge outlet for normal discharge of the bowl contents, and by-pass means leading from the bowl portion directly to said bowl discharge outlet, said by-pass means being in the form of an inverted U trap, the inlet and 40 outlet legs of said by-pass U being substantially

parallel to the inlet and outlet legs of said bowl U trap, and the discharge outlet of the by-pass outlet leg being vertically over said bowl discharge outlet.

2. As an article of manufacture, a toilet bowl 5 having a bowl bottom, a bowl discharge outlet, a main inverted U trap connecting said bowl portion to said bowl discharge outlet for normal discharge of the bowl contents, said main trap having vertically disposed side walls and by-pass means 10 leading from the bowl portion directly to said bowl discharge outlet, said by-pass means being in the form of an inverted U trap, the up-leg and down-leg of said by-pass U being substantially parallel to the inlet and outlet legs of said 15 bowl U trap, and the discharge outlet of the by-pass down-leg being vertically over said bowl discharge outlet, said by-pass up-leg having an inlet in the vertically disposed side walls of the main trap.

3. As an article of manufacture, a toilet bowl having a bowl bottom, a bowl discharge outlet, a main inverted U trap connecting said bowl portion to said bowl discharge outlet for normal discharge of the bowl contents, said main trap having 20 vertically disposed side walls and by-pass means leading from the bowl portion directly to said bowl discharge outlet, said by-pass means being in the form of an inverted U trap, the up-leg and down-leg of said by-pass U being substantially parallel to the inlet and outlet legs of said 25 bowl U trap, and the discharge outlet of the by-pass down-leg being vertically over said bowl discharge outlet, said by-pass up-leg having an inlet in the vertically disposed side walls 30 of the main trap, said by-pass means being in the form of a pair of by-pass passages located on each side of the bowl U trap.
